United States Patent Office.

JOSEPH A. RUFF, OF SOMERVILLE, MASSACHUSETTS, ASSIGNOR TO THE RUSSELL & ERWIN MANUFACTURING COMPANY, OF NEW BRITAIN, CONNECTICUT.

Design No. 3,824, dated January 25, 1870.

DESIGN FOR DOOR-ESCUTCHEON.

The Schedule referred to in these Letters Patent and making part of the same

I, JOSEPH A. RUFF, of Somerville, in the county of Middlesex, and State of Massachusetts, have invented and produced a new and original Design for a Door-Escutcheon, of which the following is a specification.

The accompanying photograph shows a design, the base of which is mainly composed of four scrolls, A A A A, in relief, and intersected by a heart-shaped device, B, at their extreme base, and by leaves C C between each pair of the scrolls A A A A.

Immediately above said scrolls is the knob-escutcheon D, surrounded by raised scroll-work.

a a' designate key-holes, of the proper size to admit their respective keys, the lower one of which key-holes,

a', is provided with a pendant, c, ornamented in harmony with the rest of the design.

The finely-matted ground d, not covered by the ornaments before referred to, is covered with similar leaf and scroll-work.

I claim, as my invention—

The design for a door-escutcheon, substantially as described and illustrated by the accompanying photograph.

JOSEPH A. RUFF.
